SAFETY MECHANISM FOR FIREARMS

John C. Garand, Springfield, Mass.

Application September 26, 1945, Serial No. 618,805

4 Claims. (Cl. 42—70)

(Granted under the act of March 3, 1883, as amended April 30, 1928; 370 O. G. 757)

1

The invention described herein may be manufactured and used by or for the Government for governmental purposes without the payment to me of any royalty thereon.

This invention relates to a firearm and more particularly to a firing mechanism thereof.

This application constitutes a continuation in part of my application Serial No. 426,036, filed January 8, 1942 now Patent 2,386,205 issued October 9, 1945.

The general object of this invention is to provide a simplified and improved firearm capable of being operated selectively as a semi-automatic or full automatic firearm and being provided with a safety mechanism.

Another object of this invention is to provide an improved firing unit assembly comprising a trigger guard, a trigger, a safety and a sear, which can be assembled to or detached from the firearm, as a unit.

The specific nature of the invention as well as other objects and advantages thereof will clearly appear from a description of a preferred embodiment as shown in the accompanying drawings in which:

Fig. 1 is a partial vertical longitudinal sectional view through mechanism of the firearm;

Fig. 1a is a continuation of Fig. 1;

Fig. 2 is an isometric view of the trigger and sear assembly;

Fig. 3 is a side view of the sear, sear spring, and safety;

Fig. 4 is an isometric view of the trigger plunger;

Fig. 5 is an elevational view of the receiver assembly viewed from the upper right side;

Fig. 6 is a vertical transverse sectional view taken on the plane 6—6 of Fig. 5;

Fig. 7 is a right side elevational view of the bolt;

Fig. 8 is a right side elevational view of the liner;

Fig. 9 is a front elevational view of the bolt;

Fig. 10 is a bottom elevational view of the bolt.

The firearm comprises a receiver assembly 1, a barrel assembly 2, a bolt assembly 3, an operating rod unit 4, a trigger assembly 5, a magazine 6 for holding cartridges 8, and a stock 7.

Receiver assembly

The receiver assembly 1 comprises essentially a receiver 9, a magazine latch 30, a magazine latch spring 32, a liner 43, a rear sight assembly 50, a combination rear sight and ejector spring 60, a cap 67 and a buffer disk 72.

2

The receiver 9, Fig. 1, is in the form of a generally cylindrical hollow member defining an axial bolt-way 10 and is provided with two downwardly depending lugs, a forward lug 11, and a rearward lug 12 through which are provided coaxial holes 13 and 14 respectively, parallel to the axis of bolt-way 10 for a purpose to appear later. In rear lug 12 is a screw hole 15 extending upward from the bottom of the lug and a counter-bored threaded hole 16 extending obliquely upward, radial to bolt-way 10, from the left side.

An ejection slot 17 leads from bolt-way 10 downwardly toward the left between lugs 11 and 12. A rounded groove 18 in the rearward face of forward lug 11 is arranged to align with slot 17 and provides clearance for a cartridge case 76 being ejected.

A magazine well 19 is provided in receiver 9 leading from bolt-way 10 upwardly toward the right, substantially opposite ejection slot 17, the receiver being extended outwardly around well 19 to form a wall 20. A crosswise undercut 21 is provided at the forward end of magazine well 19 and a longitudinal slot 23 in a rearward portion 22 of wall 20. The magazine latch 30 is pivotally secured in slot 23, by a transversely located pin 31. The coiled spring 32 is also held in assembly by pin 31, the spring being arranged to maintain the lower portion of latch 30 pivoted forwardly 30 to lock the magazine 6 in place. A slot 33 in latch 30 provides clearance for the spring 32 and shoulders 34 serve to limit the pivotal movement of the latch when the magazine well 19 is empty. The upper portion of latch 30 constitutes a thumb piece 35 arranged so that forward pressure of the thumb against the latch pivots the thumb piece 35 forward and the latch portion 30 rearward thereby disengaging the magazine 6. In the side walls 24 of magazine well 19, there are provided transversely opposite openings 25 and 26 which give access to the lower edge of magazine 6 in case it should get jammed and have to be pried out. Grooves 27 and 28 are provided in the inner face of side walls 24 for clearance of 40 the magazine.

Five inwardly projecting splines 38, preferably of equal width, are provided in the rearward half of bolt-way 10 in receiver 9, similar to the construction described in my above noted copending 50 application. These splines, as will be shown later are provided for cooperation with bolt 100, being rounded at the front corner for that purpose as shown at 39 and are equally spaced around the inside of the receiver 9. A slot 41 is provided 55 extending through the wall of the receiver in

alignment with holes 13 and 14 in lugs 11 and 12 and extending from the rear end of receiver 9 forward and opening into hole 14. This slot occupies the space between two of the splines, the width of slot 41 corresponding to the width of the space between the splines. A small notch 42 is provided in one side of slot 41 for a purpose to appear later.

A camming shoulder 44a is required in bolt-way 10 forward of splines 38 and facing rearward, i.e. toward the splines to initiate the rotating of the bolt relative to the splines. In order to obviate the difficulty of machining such a cam surface integrally in the receiver, tubular liner 43 with the rear end formed to constitute shoulders 44a and 44b is provided for assembly within receiver 9 being suitably secured in fixed location therein as by means of a set screw 45 through counter-bored threaded oblique hole 16. Shoulder 44a is rounded and is arranged to provide a camming action to bolt 100 in a manner to appear later. Shoulder 44b is square and serves as a supplementary stop to prevent excessive rotation of the bolt 100 as will be shown later. Liner 43 is cut away as at 46 to match ejector 17 and as at 47 to match magazine well 19. In the assembled relation, edges 48 of magazine well-cut 47 in liner 43 serve as shoulders against which magazine 6 is held for positioning.

The use of a liner for obtaining a camming shoulder within the bolt-way in the receiver, without involving the difficulties of making an interior radial shaving cut, provides obvious advantages in simplicity of manufacture.

The rear sight assembly 59 comprises a base 51, a plurality of sighting arms 52 integral with each other and pivotally mounted on base 51 by means of a pivot pin 53 to which they are securely attached. Arms 52 are offset to the left of the barrel center line in order to avoid interference from the magazine well wall 29 and magazine 6 when in assembly. A set screw 54 secures sight base 51 in location.

Receiver 9 is provided with an outside longitudinal groove 57 in alignment with the middle of magazine well 19. The groove extends from the magazine well rearwardly under rear sight base 51 to a radial hole 58. A slot 55 is also provided in the under side of rear sight base 51 so that when base 51 is in assembled relation on receiver 9, the slot 55 and groove 57 are contiguous. The spring 60 is provided with one end arranged at an angle as at 61 for assembly in hole 58, the spring body extending forwardly through slot 55 in rear sight base 51 and groove 57 in receiver 9. The forward end of spring 60 extends into magazine well 19 and is offset downward as at 62 for the purpose of serving as a cartridge case ejector, as will be shown later.

Slot 55 in rear sight base 51 extends upwardly into the base a sufficient distance so that the under side of rear sight pivot pin 53 projects into the slot. Flats 64 are provided on the pin 53 in spaced relation to sighting arms 52, the flats being arranged so that when one of the sighting arms is in sighting position, a corresponding flat will be engaged by spring 60 and the sighting arm will thereby be resiliently maintained in correct sighting position.

A thread 66 is provided on the rear end of receiver 9 for assembling the cap 67. This cap is provided for holding the buffer disk 72 in location at the rear end of bolt-way 10 to serve as a stop for cushioning the recoil stroke of the bolt 100. On one side of cap 67 adjacent the open end is provided an oblique lug 68 and ex-

tending through such lug is a rounded, longitudinal, radially disposed slot 69 as shown in Fig. 1.

Barrel assembly

The barrel assembly 2 comprises a barrel 80 of essentially conventional form with threads 81 for assembling to receiver 9, a chamber 82, and a bore 83. An enlarged front end bearing portion 84 is provided to serve as a bearing for a front sight comprising a sleeve 88 and a vane 89, the vane being offset to the left with respect to the axis of barrel 80 in order to align with rear sight sighting arms 52. Sleeve 88 is assembled on bearing 84 and is secured in location by a dowel pin 90 provided for that purpose.

A second bearing portion 85 with a radial gas-port 86 through the bottom thereof is provided somewhat to the rear of front sight bearing 84. A sleeve member 95, integral with a gas piston 96, is mounted on bearing 85. An aperture 97, in alignment with gas port 86, is provided extending from inside of gas piston sleeve 95 radially outward to merge with an aperture 98 extending longitudinally therefrom through gas piston 96, thereby providing a continuous passage from the bore 83 of barrel 80 through gas piston 96.

Bolt assembly

The bolt assembly 3 consists of a bolt 100, an extractor 113, a firing pin 135, and a firing pin spring 140.

Bolt 100 is of generally cylindrical form and is provided with an axial firing pin aperture 101, terminating at its forward end in a firing pin orifice 102. The juncture of firing pin aperture 101 and firing pin orifice 102 constitutes a shoulder 103.

In the rearward portion of bolt 100 is a longitudinal slot 105 extending inwardly to intersect firing pin aperture 101. The rear portion of slot 105 is extended obliquely rearward to the right as at 106 forming at the rear an oblique cam surface 107 and at the forward end of slot extension 106 a cam surface 108. The left wall 112 of slot extension 106 serves as a stop as will be shown. A slight shoulder 109 is provided in cam surface 108, all for cooperation with other parts as will be shown. A radial vent hole 110 is provided through the wall of bolt 100, just rearward of shoulder 103 to permit escape of any gases passing through the firing pin orifice 102 as a result of a punctured primer.

In the forward end of bolt 100 is a circular recess 111 coaxial with firing pin orifice 102 for receiving the head of a cartridge 8 when in engagement therewith.

An extractor groove 114 is provided along one side of bolt 100, with a pin hole 115 in the forward end of the groove and an undercut as at 116 at the rear end, all arranged for securing extractor 118 in location. The extractor has a pin 119 and a flange 120 arranged as in Fig. 10 to engage pin hole 115 and undercut 116 respectively thereby locking the extractor in operable relation to the bolt. The forward end of extractor 118 is offset in the form of a hook 121 and is arranged so as to engage an extractor groove 77 in the side of cartridge case 76, the offset 121 being beveled as at 122 on the outward face in order to permit engagement of hook 121 in a conventional extractor groove in the cartridge case 76 being seated in recess 111.

Diametrically opposite extractor 118 in bolt 100 is an ejector clearance groove 125. This groove extends from the front end of bolt 100 rearward to about the middle of the bolt at which point

it is extended sidewise to the left as at 126. This ejector clearance groove 125 and extension 126 provide clearance for ejector 62 when the bolt moves forward and rotates into the locked position.

On the rearward portion of bolt 100, five lugs 130a, 130b, 130c, 130d, and 130e are provided for cooperation with splines 38 in receiver 9 in a manner similar to that described in my above referred to copending application. However, in accordance with this invention, lugs 130a and 130b are longer than the others, lug 130a being arranged to engage camming shoulder 44a on liner 43 in receiver 9 and thereby initiate rotation of bolt 100 toward the locked position as it reaches the end of the forward stroke. Lug 130a is rounded at its forward end (not shown) to facilitate this cooperation. If, as a result of wear or for any other reason bolt 100 fails to stop its rotation in proper locking position, shoulder 44b is provided to serve as a supplementary stop by engaging lug 130b at the appropriate position. Rear corners 132 of bolt lugs 130 are rounded for a purpose to appear later.

The firing pin 135 is of cylindrical form with a large diameter rear portion 136, a medium diameter middle portion 137, and a small diameter tip 138. A shoulder 139 separates portions 136 and 137. Firing pin spring 140 is assembled over the tip 138 and middle portion 137 of firing pin 135 against shoulder 139. The firing pin 135 and the spring 140 are assembled in firing pin aperture 101 with the firing pin spring 140 engaged between shoulder 139 on the firing pin 135, and shoulder 133 in bolt 100.

Operating rod unit

The operating rod unit 4 consists of an operating rod 145, a set screw 150, an actuator 152, an actuator spring 159, and a spring guide 160.

Operating rod 145 is expanded at the forward end to form a cup or gas cylinder 146. The rearward end of the operating rod comprises a socket 147 and an operating arm 148.

Actuator 152 is of generally cylindrical form and has an axially aligned cylindrical stud 153 at the forward end arranged for engagement in socket 147 of the operating rod 145, being secured therein by set screw 153. Actuator 152 is substantially hollow, an axially coincident hole 154 extending through the actuator from the rear end to a point near the forward end. Actuator spring 159 is engaged in this hole 154. A lug 155 on the upper side of actuator 152 at the rear end is provided and arranged to be engaged in slot 105 and slot extension 103 in bolt 100, whereby the motion of actuator 152 is transmitted to the bolt 100 as will be shown later. A shoulder 156, with a forwardly facing bevel 157, is provided on the under side of actuator 152 at the rear end, the purpose of which will appear later. Flutes are provided in actuator 152 for lightening purposes.

The actuator spring guide 160 in the form of a tubular member is provided for engagement inside the rear end of the actuator spring 159. This guide has a collar 161 at its rear end and a radial lug 162, the collar 161 serving as a shoulder for engaging the rear end of actuator spring 159.

In assembly, actuator 152 is slidably engaged in aligning holes 13 and 14 in lugs 11 and 12 respectively on receiver 9. Lug 155 on actuator 152 extends generally upward through slot 41 in receiver 9 and into slot 105 in bolt 100. By this means longitudinal motion of the actuator 152 is transmitted to the bolt 100. Operating rod 145 is assembled to axial stud 153 of the actuator 152,

the gas cylinder 146 on its forward end slidably engaging gas piston 98 on barrel 80. Cap 67 is threadably assembled with buffer disk 72 therein at the end of bolt-way 10 to the rear end of receiver 9 and with slot 69 in lug 68 in axial alignment with hole 154 in actuator 152. Actuator spring guide 160 is inserted in the rear end of actuator spring 159, the forward end of the spring being passed forwardly through slot 69 in lug 68 into hole 154 in actuator 152.

Guide 160 is now forced forward compressing spring 159 and telescoping into actuator 152 until lug 162 on the guide 160 passes through slot 69 in lug 68 on cap 67. The guide is then rotated until lug 162 thereon has passed through notch 42 in receiver slot 41, and comes into alignment with a radial key-way (not shown) in cap lug 68 whereupon guide 160 is allowed to retract, seating lug 162 on spring guide 160 in lug 68 in cap 67. In this position actuator spring 159 is under considerable compression thereby maintaining actuator 152 under a positive forward stress at all times.

Trigger mechanism

25 The trigger mechanism 5 consists essentially of a trigger guard piece 164, a trigger 174, a pawl 182, a safety 190, a sear 198, a sear spring 208, a plunger 214, and a plunger spring 220.

The trigger guard piece 164 comprises a floor portion 165, a trigger guard ring 166, and an upstanding lug 167 with a vertical longitudinal bifurcation 168. A slot 169 is provided in floor portion 165 for trigger 174 and a forwardly adjoining slot 170 for safety 190. In the rearward face of lug 167 on trigger guard 164 is provided a cylindrical recess 171 below bifurcation 168 in longitudinal alignment with trigger 174 for a purpose to appear later. Also a counterbored hole 172 is provided extending upwardly through the floor and the left side of lug 167 and is arranged to align in assembly with the screw hole 15 in rear lug 12 on receiver 9. A socket screw 222 is provided for attaching trigger mechanism 5 to receiver 9 by engagement through counterbored hole 172 in the trigger guard into screw hole 15 in receiver lug 12. A groove 173 across lug 167 on trigger guard 164 is provided for engaging rearward lug 12 on receiver 9 for the purpose of aligning trigger guard 164 with receiver 9 when assembled thereto.

Trigger 174 comprises a finger piece 175, a sear stop 176, a lug 177, and is provided with forward and rearward shoulders 178 and 179 respectively, and is pivotally mounted in trigger slot 169 by means of a trigger pin 180. The ends of trigger slot 169 are arranged to cooperate with shoulders 178 and 179 on trigger 174 and thereby limit the forward and rearward motion of the trigger as desired. Pawl 182 is in the form of a yoke and is pivotally assembled by a pawl pin 188 through legs 183, astraddle sear stop 176 on trigger 174. Pawl 182 is undercut as at 184 and arranged so that when tilted rearward it partly covers sear stop 176, but when tilted forward it entirely clears the top of sear stop 176. The legs 183 of pawl 182 terminate below pawl pin 188 in the form of rearwardly curving hooks 185, arranged to engage trigger pin 180 and thereby limit the forward tipping motion of pawl 182. Two pairs of notches are provided on the forward edges of legs 183, the lower pair 186, being slightly below the pivotal axis of the pawl and the upper pair 187 being slightly above the pivotal axis. The purpose of these notches will appear later.

In assembly, safety 190 is pivotally secured in safety slot 170 by means of a safety pin 196. The lower portion of safety 190 comprises a finger piece 191 and is arranged so that it can be easily pivoted forwardly or rearwardly by the finger of the operator. The upper portion of safety 190 constitutes a stop shoulder 192, a forward or "fire" notch 193 and a rearward or "safe" notch 194.

Sear 198 is pivotally secured at its forward end 199 in the bifurcation 168 of lug 167 on trigger guard 164 by a sear pin 206. This forward end 199 of sear 198 is also bifurcated, the bifurcation 201 extending rearwardly as at 202 on the under side of the sear as shown in Fig. 3, to accommodate the sear spring 208. A rearwardly and upwardly facing beveled shoulder 203 is provided on the upper surface of sear 198 for cooperation with the bevel 157 on shoulder 156 on actuator 152 as will be shown under "operation."

Rearward of shoulder 203, two vertical notches are provided in the left side of the sear. The forward notch 204 is provided for cooperation with safety 190, the rear notch 205 for cooperation with sear stop 176 and pawl 182 on trigger 174 as will be shown.

Sear spring 208 is secured in bifurcation 201 in sear 198 by means of the sear pin 206 which passes through coils 209 of the spring. The ends of the spring are extended as at 210 and 211. Spring 208 is assembled under torsional compression, the upper end 210 being arranged to engage sear 198 in bifurcation extension 202 thereby stressing the sear upwardly, the lower end 211 of the spring being in the form of a hook as shown in Fig. 3, and arranged to selectively engage safety 190 in one or the other of notches 193 and 194, thereby resiliently locking the safety 190 in either the "fire" or "safe" position as desired and at the same time furnishing the torsional stress required to bias the sear 198 upward.

Plunger 214 is in the form of a two-tined fork, tines 215 and shank 216 being as shown in Fig. 4. Shank 216 has shoulders 217 and a short tongue portion 218. Plunger spring 220 is provided for assembly within recess 171 in trigger guard lug 167. The tongue portion 218 of shank 216 of plunger 214 fits inside the coils of spring 220, shoulders 217 being in engagement with the outer end of the spring. The tines 215 of plunger 214 straddle safety 190 and are arranged for selective engagement in notches 186 or 187 in pawl 182 as desired, being held in location by the expansive force of spring 220.

When the tines 215 of plunger 214 are engaged in lower notches 186 in pawl 182, the line of application of the resultant thrust is below the pivotal center of the pawl, hence the pawl tips forward (clockwise) till hooks 185 on the pawl legs 183 engage trigger pin 180. When tines 215 are engaged in upper notches 187, the direction of application of the resultant thrust is above the pivotal center of the pawl 182 and hence the pawl is tipped rearward (counterclockwise) until sear stop 176 is engaged in undercut 184. The purpose of all this will appear later. In either case the thrust exerted by plunger spring 220 and transmitted through plunger 214, pawl 182 and pawl pin 188 to trigger 174 is above the pivotal center of the trigger, hence trigger 174 is always stressed counterclockwise (Fig. 1). It is therefore obvious that plunger spring 220 also functions as a trigger spring.

Lug 177 on trigger 174 is arranged for limiting the downward motion of sear 198, by engagement with the underside of the sear and thereby prevent overstressing or shearing of sear spring 208.

Stock

The stock 7 is of conventional type adapted to fit the above described mechanism.

Operation

The above described firearm is of the gas operated type, the gas being taken from the bore 83 of barrel 80 through gas port 86 into gas cylinder 146 on the end of operating rod 145, the gas pressure developed in the gas cylinder forcing the operating rod 145 and the actuator 152 rearward.

As actuator 152 moves rearward, actuator spring 159 is subjected to additional compression, hence at the end of the rearward stroke spring 159 is under maximum compression. Therefore the full compressive force of the spring is exerted forwardly against actuator 152. This force causes the actuator to immediately return forward whereupon bevel 157 on shoulder 156 on actuator 152 engages beveled shoulder 203 on sear 198, camming the sear downward, but sear stop 176 on trigger 174 engages the sear just to the rear of trigger slot 169 thereby preventing further downward motion and retaining shoulder 203 thereon in engagement with shoulder 156 on the actuator so that actuator 152 is stopped immediately after bolt 100 is locked in firing position, but while the bolt is still about one-half inch from the extreme forward position.

When finger piece 175 of trigger 174 is pulled back, sear stop 176 on the trigger is pivoted forward out of engagement with sear 198 into alignment with trigger slot 169 thereby permitting the sear to move downward under the camming force of actuator 152, which, being freed from engagement by the sear, moves forward under the thrust of actuator spring 159. Lug 155 on the actuator engages firing pin 135 driving it forward to strike the cartridge.

As soon as the cartridge 8 is fired, the gas pressure developed tends to force the cartridge case 76 and bolt 108 rearward. As soon as the bullet of cartridge 8 has passed gas port 86 in the barrel 80, gas escapes through the port 86 and aperture 97 into gas cylinder 146 on operating rod 145 driving the entire operating rod assembly rearward to repeat the cycle above described.

In order to obtain semi-automatic fire, pawl 182 on trigger 174 is normally pivoted forwardly by engagement of plunger 214 in lower notches 186 on the legs 183 of the pawl. In this position, the pawl 182 is arranged so that it comes into resilient engagement with the forward face of trigger notch 205 before sear stop 176 on trigger 174 passes out of engagement with sear 198 into trigger notch 205. When actuator 152 has moved rearward on the recoil stroke, and shoulder 156 thereon has passed out of engagement with shoulder 203 on the sear 198, then the sear is pivoted upward by sear spring 208, and pawl 182 snaps forward under the forward edge of trigger notch 205 so that shoulder 156 on actuator 152 will be engaged by shoulder 203 on sear 198, and the sear will be maintained in this high position until finger piece 175 on trigger 174 is released, whereupon pawl 182 moves out of engagement with the sear which drops into engagement with sear stop 176 on trigger 174, ready for firing by pulling the trigger.

If it is desired to have the firearm operate fully automatic, the trigger assembly 5 is removed from the firearm, and the plunger 214 is moved into engagement in upper notches 187 in pawl 182 and the trigger assembly reassembled to the firearm. In this position the pawl is pivoted rearwardly and in all positions of the trigger 174 and is maintained in alignment with trigger notch 205, out of the way of the sear, so that on the forward stroke of the actuator, sear 198 will be cammed out of engagement therewith unless trigger 174 has been released and sear stop 176 thereon has again moved into the path of the sear.

Safety 190 is arranged so that when finger piece 191 is pivoted rearwardly, stop shoulder 192 is forward of safety notch 204 and prevents the sear 198 from dropping to permit shoulder 203 thereon from disengaging shoulder 156 on actuator 152. In this position, the firearm cannot be fired, for the safety stop shoulder 192 holds sear 198 in an even higher position than would sear stop 176 on the trigger 174. When safety 190 is in the above described position, lower end 211 of sear spring 298 is engaged in rearward notch 194 of the safety. This is the "safe" position. In the forward or "fire" position finger piece 191 of safety 190 is pivoted forward, spring end 211 is engaged in forward notch 193 of the safety and stop shoulder 192 thereon, now being in alignment with safety notch 204 in sear 198, is out of the way of the sear, thereby permitting downward motion of the sear.

I claim:

1. In a firearm having a firing mechanism, the improvement comprising, a sear pivotally mounted in the firearm and arranged to retain the firing mechanism in a cocked position, said sear being pivotally biased downwardly by the firing mechanism, said sear having a trigger notch and a safety notch therein defined by forward and rearward edges, a trigger pivotally mounted in the firearm underlying said sear and having an upstanding trigger projection thereon, said projection being constructed and arranged so that in the normal position of the trigger and the cocked position of the firing mechanism the trigger projection engages the sear adjacent the rear edge of said trigger notch to prevent downward movement of the sear and in the retracted position of the trigger the trigger projection aligns with said trigger notch thereby permitting downward movement of the sear, a pawl pivotally mounted on the trigger at a distance above the pivotal center of said trigger, said pawl lying adjacent said trigger projection and extending upwardly toward said sear, said pawl having a pair of grooves on the forward edge thereof, a plunger resiliently mounted in the firearm and selectively engaging one of said grooves, said trigger being biased toward its relaxed position by said plunger, said grooves being oppositely disposed relative to the pivotal center of said pawl so that said pawl is selectively displaced rearwardly into alignment with said trigger notch irrespective of the position of the trigger or said pawl is selectively displaced forwardly to engage the forward edge of said trigger notch as said trigger is pulled, a safety pivotally mounted in said firearm underlying said sear, said safety being provided with a "safe" groove and a "fire" groove and having an upstanding safety projection thereon, and an exterior spring mounted in said trigger guard and operating between said sear and said safety, said spring having a hooked end selectively engaged in one of said grooves in said safety, said spring and said safety being constructed and arranged so that when said spring is engaged in said "safe" groove in said safety the safety projection underlies the sear adjacent the safety notch in said sear thereby preventing downward movement of the sear and when said spring is engaged in said "fire" groove in said safety the safety projection aligns with said safety notch in said sear thereby permitting downward movement of the sear.

3. In a firearm having a firing mechanism, the improvement comprising, a sear pivotally mounted in the firearm and arranged to retain the firing mechanism in a cocked position, said sear being pivotally biased downwardly by the firing mechanism, said sear having a safety notch therein, a safety pivotally mounted in said firearm underlying said sear, said safety being provided with a "safe" groove and a "fire" groove and having an upstanding safety projection thereon, and a trigger guard having a spring mounted thereon, said spring being resiliently engaged between said trigger guard and said sear, said spring having a hooked end selectively engaged in one of said grooves in said safety, said spring and said safety being constructed and arranged so that when said spring is engaged in

safety, the safety projection underlies the sear adjacent the safety notch to prevent downward movement of the sear and in the "fire" position of the safety, the safety projection aligns with said safety notch thereby permitting downward movement of the sear.

2. In a firearm having a firing mechanism, the improvement comprising, a sear pivotally mounted in the firearm and arranged to retain the firing mechanism in a cocked position, said sear being pivotally biased downwardly by the firing mechanism, said sear having a trigger notch and a safety notch therein defined by forward and rearward edges, a trigger pivotally mounted in the firearm underlying said sear and having an upstanding trigger projection thereon, said projection being constructed and arranged so that in the normal position of the trigger and the cocked position of the firing mechanism the trigger projection engages the sear adjacent the rear edge of said trigger notch to prevent downward movement of the sear and in the retracted position of the trigger the trigger projection aligns with said trigger notch thereby permitting downward movement of the sear; a pawl pivotally mounted on the trigger at a distance above the pivotal center of said trigger, said pawl lying adjacent said trigger projection and extending upwardly toward said sear, said pawl having a pair of grooves on the forward edge thereof, a plunger resiliently mounted in the firearm and selectively engaging one of said grooves, said trigger being biased toward its relaxed position by said plunger, said grooves being oppositely disposed relative to the pivotal center of said pawl so that said pawl is selectively displaced rearwardly into alignment with said trigger notch irrespective of the position of the trigger or said pawl is selectively displaced forwardly to engage the forward edge of said trigger notch as said trigger is pulled, a safety pivotally mounted in said firearm underlying said sear, said safety being provided with a "safe" groove and a "fire" groove and having an upstanding safety projection thereon, and an exterior spring mounted in said trigger guard and operating between said sear and said safety, said spring having a hooked end selectively engaged in one of said grooves in said safety, said spring and said safety being constructed and arranged so that when said spring is engaged in said "safe" groove in said safety the safety projection underlies the sear adjacent the safety notch in said sear thereby preventing downward movement of the sear and when said spring is engaged in said "fire" groove in said safety the safety projection aligns with said safety notch in said sear thereby permitting downward movement of the sear.

said "safe" groove in said safety and the safety projection underlies the sear adjacent the safety notch in said sear thereby preventing downward movement of the sear and when said spring is engaged in said "fire" groove in said safety the safety projection aligns with said safety notch in said sear thereby permitting downward movement of the sear.

4. In a firearm having a firing mechanism, a detachable trigger assembly comprising, a trigger guard, means for detachably securing said trigger guard to said firearm, a sear pivotally mounted on the trigger guard and arranged to retain the firing mechanism in a cocked position, said sear being pivotally biased downwardly by the firing mechanism, said sear having a trigger notch and a safety notch therein defined by forward and rearward edges, a trigger pivotally mounted in the trigger guard underlying said sear and having an upstanding trigger projection thereon, said projection being constructed and arranged so that in the normal position of the trigger and the cocked position of the firing mechanism the trigger projection engages the sear adjacent the rear edge of said trigger notch to prevent downward movement of the sear and in the retracted position of the trigger the trigger projection aligns with said trigger notch thereby permitting downward movement of the sear, a pawl pivotally mounted on the trigger at a distance above the pivotal center of said trigger, said pawl lying adjacent said trigger projection and extending upwardly toward said sear, said pawl having a pair of grooves on the forward edge thereof, a plunger resiliently mounted in the firearm and selectively engaging one of said grooves, said trigger being biased toward its relaxed position by said plunger, said grooves being oppositely disposed relative to the pivotal center of said pawl so that said pawl is selectively displaced

rearwardly into alignment with said trigger notch irrespective of the position of the trigger or said pawl is selectively displaced forwardly to engage the forward edge of said trigger notch as said trigger is pulled, a safety pivotally mounted in said trigger guard underlying said sear, and means for selectively positioning said safety in either a "safe" position or a "fire" position, said safety having an upstanding safety projection thereon, said safety projection being constructed and arranged so that in the "safe" position of the safety the safety projection underlies the sear adjacent the safety notch to prevent downward movement of the sear and in the "fire" position of the safety, the safety projection aligns with said safety notch thereby permitting downward movement of the sear.

JOHN C. GARAND.
